CLAIM

The ornamental design for a display screen with animated graphical user interface, as shown and described.

DESCRIPTION

The patent or application file contains at least one drawing executed in color. Copies of this patent or patent application publication with color drawing(s) will be provided by the Office upon request and payment of the necessary fee.

1. Display screen with animated graphical user interface

16.1: Front

16.7: Front

16.8: Front

16.9: Front

16.10: Front

16.11: Front

The appearance of the transitional image sequentially transitions between the images shown in Figs. 16.1-16.11. The process or period in which one image transitions to another image forms no part of the claimed design.

The broken lines in the drawings depict environmental structure and form no part of the claimed design. The features fully bounded by broken lines form no part of the claimed design.

(Continued)

The outer edge of the underlying display screen is understood to be congruent with the black rectangular border of the graphical user interface.
